United States Patent Office.

JOHN M. CULVER, OF WALLINGFORD, CONNECTICUT, ASSIGNOR TO HALL, ELTON & CO., OF SAME PLACE.

Design No. 4,788, dated April 11, 1871.

DESIGN FOR A FORK OR SPOON-HANDLE.

The Schedule referred to in these Letters Patent and making part of the same.

To all whom it may concern:

Be it known that I, JOHN M. CULVER, of Wallingford, in the county of New Haven and State of Connecticut, have invented a new Design for Spoon and Fork-Handle; and I do hereby declare the following, when taken in connection with the accompanying drawing and the letters of reference marked thereon, to be a full, clear, and exact description of the same, and which said drawing constitutes part of this specification, and represents a front view of the handle.

This invention relates to a design for the handle of spoons and forks, with especial reference to the outline, irrespective of the ornamentation, and consists in the peculiar shape of the handle, as shown in the accompanying illustration.

On the handle at *a* the enlargement commences by a circular projection on each side; then flaring up to

another circular portion, *d*; then from this circular portion up again, still flaring, to the upper portion *c*, where the top is quickly drawn in, forming an angle at *c*, all as fully shown in the accompanying illustration.

This shape may be ornamented in any desirable manner, the ornamentation being no part of the design.

I claim as my invention—

The design for spoon and fork-handle, as herein described, and shown in the accompanying illustration.

JOHN M. CULVER.
